UNITED STATES PATENT OFFICE

WILLIAM FOLWELL HOISINGTON, OF PARIS, FRANCE, ASSIGNOR TO GOWER H. REES, OF LONDON, ENGLAND

RADIORECEIVER

Application filed November 25, 1927, Serial No. 235,525, and in Great Britain December 1, 1926.

This invention relates to radio receivers and has particular application to those of the portable type.

The principal object of the invention is to increase the volume, selectivity and quality of radio receivers, and to increase the range of frequencies over which radio receivers may be efficiently operated.

According to a feature of the invention the 10 tuned secondary winding of a transformer connected in an antenna circuit or the tuned loop antenna is connected to the input circuit of a high frequency electronic amplifier whose output circuit is variably coupled to the 15 input circuit of an electronic detector by a transformer the windings of which are relatively adjustable to vary the degree of coupling therebetween, the secondary winding thereof being tuned. The inductance of the 20 two windings is approximately equal and the inductance of each is approximately equal to that of the loop antenna or the secondary associated with the antenna circuit.

More than one stage of high frequency amplification may of course be employed, the last stage being coupled to the detector as described.

In accordance with another feature of the invention the radio receiver is provided with a 25 radio wave interceptor made in two sections, one being of less number of turns than the other and the two sections being separated by several inches on a frame or other support. The smaller section has an inductance 30 approximately one third that of the larger section. Each section is tapped, and is so associated with cooperating switching means that when only the smaller section or a portion thereof is used for reception the larger 35 section is short-circuited.

The wave interceptor embodying this invention has a wave length range, the maximum of which is about ten times that of the minimum and there is no appreciable loss 40 due to dead end or harmonic resonance.

The accompanying drawing illustrates a portable radio receiver embodying the features of the invention.

Referring to the drawing, the radio receiver 45 comprises a radio wave interceptor

which takes the form of a loop antenna made up of two sections 1 and 2, a high frequency amplifier 3, a detector 4, two low frequency amplifiers 5 and 6 and a loud speaker 7.

The loop antenna suitable for receiving 55 over a wave length range from 200 to 2000 meters will be more particularly described. The upper section 1 consists of 26 turns of No. 22 S. W. G. enamelled double cotton covered copper wire tapped at the twelfth 60 turn from the filament end, with the turns spaced a distance equivalent to the diameter of the wire. The lower section 2, which is spaced approximately two inches from the upper section, consists of 69 turns of the 65 same wire wound with the adjacent turns close together. The loop antenna is controlled by a switch 8 and is tuned to the wave length to be received by a variable condenser 9 of the square law type having a maximum capacity of .0003 microfarad.

The upper portion of section 1 of this particular loop antenna is suitable for receiving waves of from approximately 200 to 400 metres, and the whole of section 1 is suitable 75 for receiving waves of from approximately 350 to 550 metres. When section 1 only or a portion thereof is utilized, the whole of section 2 is short-circuited to avoid interference therefrom upon section 1 due to the natural frequency of section 2, and the damping effect upon section 1 from the short-circuited section 2 is avoided by the proper spacing of the two sections. For the reception of waves of from approximately 850 80 to 1500 metres, all of section 1 is connected in series with the upper portion of section 2. The entire two sections 1 and 2 connected in series are employed for receiving waves of from approximately 1400 to 2000 metres. 90

To make the loop antenna suitable for receiving different ranges of wave lengths, the sections thereof and their tappings can, of course, be appropriately chosen.

This will be evident from considering the 95 various circuits that may be established by switch 8. The arm of switch 8 carries two permanent contacts 31 and 32. Contact 31 is connected to the filament of tube 3 and to the condenser 9. Contact 32 is connected 100

- to the end of the upper portion of section 2 of the antenna. When the arm of switch 8 is moved on to the first pair of contacts, which are shown on the extreme left of the switch, the following connections are made:—grid of tube 3, upper portion of winding 1, contact 31 of switch 8, filament of tube 3. Section 2 of the antenna is short-circuited over contact 32. When the arm of switch 8 is moved to occupy the second or neighbouring pair of contacts the former circuit is broken and instead the following established:—grid of tube 3, section 1 (both portions) contact 31 of switch 8 to condenser 9 and filament of tube 3. In this position of the switch the whole of section 2 is again shortcircuited exactly as in the first position. In the third position of switch 8 obtained by moving the switch to the right one step to occupy the next pair of terminals, the following circuit is made:—grid of tube 3, section 1 (both portions), contact 32, upper portion of section 2, contact 31 to condenser 9 and filament of tube 3. The fourth or last position of switch 8 is on the extreme right pair of contacts. In this position the whole of sections 1 and 2 are in parallel with condenser 9. The circuit is from condenser 9 over section 1 to contact 32 of switch 8, over section 2 to contact 31 of switch 8 and to condenser 9.
- The opposite plates of variable condenser 9 are connected to the filament and grid respectively of the high frequency amplifier 3.
- The output circuit of amplifier 3 may be coupled to the input circuit of detector 4 by either of two transformers 12 or 13 controlled by a double-throw four-pole switch 14. There are two active positions for switch 14. In one position its contact arms all extend upwardly to engage the terminals of the left and right windings of transformer 12 as will be obvious from the drawing. In the other active position of switch 8, the contact arms extend downwardly the outer ones engaging the extreme left and right terminals of the left hand winding and right hand winding of transformer 13. The inner contact arms, in this position of the switch, engage blank contacts 33. Transformer 12 is employed when antenna section 1 or only a portion thereof is utilized for reception. Transformer 13 is employed when both antenna sections or section 1 and the upper portion only of section 2 are connected in circuit for reception.
- When transformer 12 is connected in circuit, both windings of transformer 13 are short-circuited to avoid interreference therefrom upon transformer 12 due to the natural frequency of transformer 13. The damping effect upon transformer 12 from the short-circuited windings of transformer 13 is avoided by proper spacing of the two transformers which are mounted at right angles.

The primary and secondary windings of each transformer employed in a radio receiver used for several months consist of honeycomb wound air core coils, the two coils of a transformer being mounted side by side and being relatively adjustable for a purpose heretofore alluded to and more particularly hereinafter described.

In the practical radio receiver referred to, the honeycomb wound coils employed had an inside diameter of 2 inches, the wire being of No. 26 S. W. G. single cotton covered copper. Each coil of transformer 12 had 75 turns and each coil of transformer 13 had 300 turns.

When either transformer is connected in circuit variable condenser 15 is connected in closed circuit relation to the secondary winding of the connected transformer and is employed to tune such secondary to the wave length to be received. This condenser 15 may be of the square law type and have a maximum capacity of .0003 microfarad.

The tuned secondary of high frequency transformer 12 or 13 is connected through condenser 16 to the grid of detector 4, while the usual leak resistance 17 for condenser 16 is connected across the grid and the filament of detector 4.

The output circuit of detector 4 is coupled to the input circuit of low frequency amplifier 5 by a transformer 18, the primary winding of which is shunted by a by-pass condenser 19 for the high frequency components of the detected signal modulated wave.

A transformer 21 couples the output circuit of amplifier 5 to the input circuit of amplifier 6.

The output circuit of amplifier 6 has connected therein loud speaker 7 shunted by condenser 23.

Plate current for the various amplifiers and the detector is supplied from a high tension battery 25.

Grid biasing potential for the grids of the low frequency amplifiers is supplied from battery 27.

Current for heating the filaments of the several amplifiers and the detector is supplied from battery 28, the circuit of which contains a switch 29.

The high frequency apparatus shown within the dotted rectangle 30 is shielded from the antenna sections 1 and 2 and from the low frequency apparatus of the radio receiver to prevent detrimental reaction.

When tuning the illustrated radio receiver for a new station having a wave length between 200 and 400 metres, antenna switch 8 is set to its first position (left), switch 14 set to connect transformer 12 in circuit and switch 29 is closed. Condenser 9 is then adjusted to find the station and condenser 15 is adjusted to tune the high frequency transformer secondary to approximately the wave length of the station, after which the coupling

between the coils of transformer 12 is adjusted to bring up the volume and quality of the received signal and at the same time making fine adjustments of both tuning condensers 9 and 15 to get the best possible results of 5 volume and quality of signal.

Varying the coupling between the windings of either of the high frequency transformers makes possible very large increase in 10 volume and quality of the received signal and causes the radio receiver to be more highly selective. The reason for this is believed to be that the adjustable coupling permits a very fine adjustment of the damping upon the 15 transformer secondary circuit thereby making it possible to obtain much sharper tuning therein which increases not only the strength of the signal but also the quality thereof. Sharper tuning of the transformer secondary 20 allows the high frequency amplifier and the detector to operate most efficiently at any frequency. It follows that the selectivity of the radio receiver is also very greatly increased.

It has been demonstrated that by making 25 the windings of the high frequency transformer relatively adjustable to vary the coupling between the primary and secondary windings, as much as a 50 per cent increase of signal strength is obtained and the quality 30 of the signal is improved to substantially the same degree. It is evident therefore that signals can be effectively received from more distant stations than is possible without employing the invention herein described.

35 From the description and explanation given above, it is obvious that the invention may be employed in radio receivers for receiving radio waves of other wave length ranges.

40 Thus the invention has been applied to a radio receiver with which the same improved results have been obtained in receiving wave lengths as low as 30 meters.

Should it be desired to make a radio receiver 45 to operate over a narrower wave length range one or the other of the antenna sections may be omitted and the corresponding high frequency transformer could then be omitted without departing from the spirit of the invention.

50 What is claimed is:—

1. In a portable radio receiver, the combination of a sectional loop antenna, switching means for selecting one or more sections of 55 said antenna and for connecting said section to the input circuit of a first three electrode tube, a second three electrode tube, and means for coupling the output circuit of the first tube to the input circuit of the second tube comprising a transformer having relatively adjustable primary and secondary windings, the inductance of each winding being approximately equal to the inductance of the corresponding antenna section.

65 2. In a radio receiver the combination of

a sectional loop antenna, switching means for selecting one or more sections of said antenna and for connecting said sections to the input circuit of a three-electrode electron discharge device, a second three-electrode electron discharge device, means for coupling the output circuit of the first tube to the input circuit of the second tube comprising a plurality of transformers matched to correspond in electrical characteristics to 70 certain sections of said antenna, and switching means for selectively connecting a desired one of said transformers in circuit.

3. A receiver according to claim 2 where- 75 in the second mentioned switching means serves to short-circuit the transformer which is not connected in circuit.

4. A portable radio receiver comprising a 80 loop antenna, a first electron discharge tube having its input circuit connected to said antenna, a second electron discharge tube, means for coupling the second tube to the first tube comprising a transformer having a primary winding and a secondary winding 85 each of said windings having approximately 90 the same inductance as said antenna.

5. In a radio receiving set, a switching 95 means, an amplifier tube, an antenna comprised in a plurality of spaced-apart sections, each connected to different contacts in said switching means, a section of said antenna being, in one position of said switching means, adapted to be separately connected to the input circuit of said amplifier, in which position of the switch another section of the 100 antenna is short-circuited over said switch and said switching means in another position connecting a plurality of such antenna sections to the input circuit of said amplifier.

6. In a radio receiving set, a switching 105 means, a plurality of sets of contacts separately engageable by said switching means, an amplifier tube, an antenna comprised in a plurality of spaced-apart sections each connected to a different one of said sets of contacts, which are interconnected so that in one position of engagement of the switching means a certain portion of said antenna is connected through said switching means to 110 said amplifier tube and another portion of said antenna is short-circuited, whereas in another position of said switching means a greater portion of said antenna is connected through said switching means to said amplifier, whilst another portion of said antenna is short-circuited.

7. In a radio receiving set, a loop antenna having a plurality of sections, a tube amplifier, an input circuit and an output circuit for 115 said amplifier, means for selectively associating said sections with said input circuit, means for selectively inserting in said output circuit a plurality of transformer windings to correspond in wave length with the chosen 120 of said sections.

8. In a radio receiving set, a loop antenna having a plurality of sections, a tube amplifier, an input circuit and an output circuit for said amplifier, means for selectively associating said sections with said input circuit, means for selectively inserting in said output circuit a plurality of transformer windings to correspond in wave length with the chosen of said sections, the inductance of the primary and secondary windings of any of the transformers when in operative connection being equal and being also equal approximately to the inductance of the sections which are in operative connection.
9. A radio receiver comprising a high frequency amplifier, a detector, a plurality of transformers, switching means for connecting any one of said transformers in circuit to couple said amplifier and said detector and for short circuiting the windings of one of the transformers when another thereof is connected in circuit, a loop antenna connected to said amplifier comprising a plurality of separate sections wound in spaced relationship and provided with taps intermediate its ends, and switching means for connecting said section in series for receiving signals, said switching means also serving to short circuit the sections of the antenna not being used for receiving signals.

In testimony whereof, WILLIAM FOLWELL HOISINGTON has signed his name to this specification.
